(57) **CLAIM**

The ornamental design for food drier as shown and described.

DESCRIPTION

1. Food drier
2. Food drier
- 1.1 : Perspective
- 1.2 : Front
- 1.3 : Right
- 1.4 : Left
- 1.5 : Perspective
- 1.6 : Back
- 1.7 : Top
- 1.8 : Bottom
- 2.1 : Perspective
- 2.2 : Front
- 2.3 : Right
- 2.4 : Left
- 2.5 : Perspective
- 2.6 : Back
- 2.7 : Top
- 2.8 : Bottom

The parts delineated by means of dashed lines form no part of the claimed designs.
